UNITED STATES PATENT OFFICE.

HEZEKIAH D. JONES, OF ONARGA, ILLINOIS, ASSIGNOR OF ONE-FOURTH
TO HENRY E. BIBBENS, OF SAME PLACE.

CHECK-ROW ATTACHMENT FOR CORN-PLANTERS.

SPECIFICATION forming part of Letters Patent No. 274,612, dated March 27, 1883.

Application filed August 21, 1882. (No model.)

To all whom it may concern:

Be it known that I, HEZEKIAH D. JONES, a citizen of the United States of America, residing at Onarga, in the county of Iroquois and State of Illinois, have invented certain new and useful Improvements in Check-Row Attachments for Corn-Planters, of which the following is a specification, reference being had therein to the accompanying drawings.

10 My invention relates to a check-row attachment for corn-planters; and it consists in a long, narrow, rectangular frame. The rear end of the frame passes around a wheel on the plane of its axis. Said wheel is provided with an 15 axle which has its bearings in the sides of the frame. The axle extends out on either side of the frame, and is provided with two cranks—one on each side. The cranks are rigidly secured to the axle and point in opposite directions. To each of these cranks is secured the 20 end of a cord, chain, or wire, which extends forward and passes around concaved pulleys on the forward sides of the frame. That part of the cord that passes immediately in front 25 of the frame is provided in its center with a button. A vibrating arm is pivoted to a cross-piece uniting the frame. The upper part of said arm is in the form of a C-shaped hook. To the top of the arm is secured a ball-weight, 30 to facilitate vibratory action of the arm and insure a stroke of the slide to the full capacity of the arm. Two short arms are pivoted to the bottom of the vibratory arm. These short arms extend outward in opposite directions on 35 the seed-slide bar, and are secured thereto by staples. The slide-bar rests in depressions formed on the under side of the frame.

The device is adapted for attachment to any 40 form of corn-planter. It will be seen by reference to the accompanying drawings that it can be easily attached or detached. By detaching the short arms from the slide-bar my improvement can be removed from the planter, or it can be engaged by uniting said arms to 45 the slide-bar.

Referring to the drawings, Figure 1 is a perspective view of a corn-planter provided with my attachment. Fig. 2 indicates a perspective of the front end of the frame, showing 50 the vibrating arm, cord, button, and pulleys. Fig. 3 shows in perspective the forward end

of the frame provided with a modification of my invention.

In the accompanying drawings similar letters refer to similar parts throughout the several views. 55

A is the slide-bar.

B is the vibrating arm, and C the C-shaped hook formed on the top thereof. 60

C' is a weight-ball on top of the hook.

D represents the pivot securing the arm B to the frame cross-piece. 65

E E are short arms pivoted at F to arm B.

G G are staples securing the outer ends of arms E E to the slide-bar A. 65

H is the front end of the frame; I I, the forward side bars, and L L the rear bars, of said frame.

J J are cross-rods, serving to unite the frame-pieces I I and L L. 70

K is a cross-block uniting the sides of frame I I, and against which the forward ends of pieces L L abut. The vibrating arm B is pivoted to the front side of the cross-block K.

M M are pulleys projecting outward from 75 the sides of the frame I I.

N is a button fixed to the front cross-piece of the cord O.

P is the wheel within the frame, and Q is 80 one of the cranks, keyed to the axle thereof.

In the modification, Fig. 3, P' represents a bar pivoted at Q' to the top of vibrating arm B'. R is a pivot connecting the bottom of one of the forks c to the cross-bar P'. S is a pivot uniting the fork to the cross-piece K' of the 85 frame. T is a pivot near the center of fork c', and U is a pivot below pivot T, which connects the lower end of fork c' to the cross-block K'. V is a socket-plate rigidly united to the sliding bar A. The bottom of the arm 90 B' in this modification is adapted to fit in the socket of plate V, and thereby receive and impart motion.

The object of the modification is to expedite the action of the slide-bar A, and consequently 95 the dropping capacity of the device.

The mechanism shown in Figs. 1 and 2 produces one right and one left movement of the bar A by a single revolution of the wheel P. In the modification one revolution of the wheel 100 P produces two right and two left movements, in their order, of the bar A.

My invention, after having been attached to a corn-planter in the manner hereinbefore stated, is operated as follows: The forward movement of the planter causes the following 5 wheel P to revolve, which action operates the cranks Q, and through said cranks the cord O is given a reciprocating motion. The button N, being secured to the cord, is also given a corresponding motion. This button, in its reciprocating course, is drawn through the C-shaped hook of the arm, thereby imparting to 10 said arm a vibratory motion, and thus causing the seed-slide A to perform its well-known function in the seed-boxes. At each revolution of the cranks Q the cord is moved backward and forward, and consequently the button is given a forward and backward movement. It must therefore be apparent that each move 15 of the button causes the arm to vibrate in its moving direction.

The special advantages that I claim for this machine are, first, doing away with unreeling and stretching eighty rods, or more, of rope; second, doing away with all side draft on the 20 team, and avoiding getting on and off the planter at each end of the field.

Having thus described my invention and set forth its advantages, I claim as new and desire to secure by Letters Patent—

30 1. In a check-row attachment for corn-planters, the combination of the operating-wheel P,

journaled in the side bars, LL, carrying cranks Q Q, for operating the seed-slide A through the medium of the cord O, button N, pulleys M M, and vibrating arm B, substantially as 35 set forth.

2. In a check-row attachment for a corn-planter, the vibrating arm B, pivoted to cross-block K, said arm being provided with the C-shaped hook and ball C', and the arms E E, 40 pivoted at F and secured by staples G to the seed-slide A, the arm B being actuated by the button N, in the manner and for the purposes specified.

3. In a check-row attachment for corn-planters, the combination of the slide A, arms E E, 45 vibrating arm B, pivot D, cross-block K, frames H I L, and cross-rods J, the forward end of frame L abutting against the cross-block K, the several parts being united in the manner 50 and for the purposes specified.

4. The arm B, constructed as described, and pivoted to cross-block K, and the short arms E E, in combination with the seed-slide A, substantially as described, and for the purposes 55 specified.

In testimony whereof I affix my signature in presence of two witnesses.

HEZEKIAH D. JONES.
